UNITED STATES PATENT OFFICE.

HENRY J. FRITZ, OF BLUFFTON, INDIANA.

POST-BRACE.

No. 921,534.

Specification of Letters Patent.

Patented May 11, 1909.

Application filed May 13, 1908. Serial No. 432,623.

To all whom it may concern:

Be it known that I, HENRY J. FRITZ, a citizen of the United States, residing at Bluffton, in the county of Wells and State of Indiana, have invented new and useful Improvements in Post-Braces, of which the following is a specification.

This invention relates to post braces particularly adapted for bracing corner posts for fences, for gate posts, and for other purposes wherein it is found applicable and the objects thereof are to provide a post brace which shall be simple in its construction, strong, durable, efficient in its use, readily set up, inexpensive to manufacture, and conveniently tightened when occasion so requires.

With the foregoing and other objects in view, the invention consists of the novel construction, combination and arrangement of parts hereinafter more specifically described and illustrated in the accompanying drawings, wherein is shown the preferred embodiment of a post brace in accordance with this invention, but it is understood that changes, variations and modifications can be resorted to which come within the scope of the claims hereunto appended.

In the accompanying drawings wherein like reference characters denote corresponding parts throughout the several views:

Figure 1 is a side elevation of a post brace in accordance with this invention. Fig. 2 is a plan of the tightening device and coupling member. Fig. 3 is a perspective view of the brace member. Fig. 4 is a like view of the connecting rod between the brace member and the tightening device. Fig. 5 is a similar view of a foot plate for the lower end of the brace member. Fig. 6 is a perspective view of a novel form of post. Fig. 7 is a plan of a modified form of tightening device. Figs. 8 and 9 show the adaptation of a brace member in accordance with this invention in connection with a wooden post. Fig. 10 is a sectional detail of one end of a modified form of brace member. Fig. 11 is a side elevation showing the post brace with an adaptation of the modified form of brace member shown in Fig. 10, and Fig. 12 is a perspective view of the upper end of the modified form of brace member.

Referring to Figs. 1 to 6 in detail, 1 denotes a post substantially V-shaped in cross section and carrying near its top an abutment screw 2. The lower end of the post 1 is formed

with a pair of angularly disposed protuberances 3 constituting anchors. Abutting against the post 1 as well as the screw 2 is a V-shaped brace member 4, the upper end of the member straddling the post 1, as clearly shown in Fig. 1. The lower end of the brace member 4 is flattened as at 5 to form a foot, and the latter is apertured as at 6 for a purpose to be hereinafter referred to. The foot 5 is adapted to be mounted upon the flanged supporting plate 7, the latter resting upon the ground and having its upper face provided with a groove 8. Surrounding the post 1 in proximity to the ground is a coupling formed of two detachable members 9, 10, each of which is provided with an eye at one end as at 11 and a hook at the other end as at 12, the hook of one member entering the eye of the other member whereby the members 9 and 10 are connected together. By setting up the coupling member with a pair of separable or detachable sections, it can readily be connected to or removed from the post 1 when occasion so requires. The reference character 13 denotes a connecting rod provided with the hooked ends 14, 15. That end of the connecting rod 13 which is provided with a hook 14 is adapted to be seated in the groove 8 and when so positioned the hook 14 extends through the opening 6 in the foot 5, as clearly shown in Fig. 1. The hook 15 of the rod 13 is adapted to engage with a tightening device, the latter consisting of a shiftable plate 16 having an aperture 17 through which extends the hook 15 and the said plate 16 is furthermore provided with a vertical flange 18 having an opening through which extends a screw-threaded bolt 19 having a hooked end 20 which engages with the member 10 of the coupling. Upon the screw-threaded portion of the bolt 19 is mounted an adjusting nut 21. When the parts are set up in the manner as shown in Fig. 1 the brace member 14 can be tightened by adjusting the nut 21 toward the post and loosened when the nut is shifted away from the post.

In Fig. 7 the modified construction of tightening device is shown and in this connection it will be stated that the connecting rod which is indicated by the reference character 22 has one end 23 screw-threaded in lieu of being provided with a hook and upon said screw-threaded portion is mounted one end of a turn buckle 24. The other end of said turn buckle 24 engages with the screw-threaded portion 25 of a hook-shaped bolt

26, the bolt being adapted to engage with the member 10 of the coupling.

In Figs. 8 and 9 of the drawing, the brace member 1 is shown employed in connection with a wooden post 27 and it will be stated in such particular that the upper end of the brace member is adapted to enter the post.

Figs. 10, 11 and 12 disclose a modified form of brace member and in this connection it will be stated that the modified form of brace member which is indicated by the reference character 28 is tubular in contour and carries a cap piece 29 provided with a protuberance 30 adapted to enter the post 31. The lower end of the brace member is flattened as at 32 to provide a foot which is apertured to receive the hooked end 14 of the connecting rod 15. The tightening device and coupling as shown in Fig. 11 is the same as that shown in Fig. 1.

The tightening device enables the post to be positioned in a perpendicular manner as will be evident, for the reason that if the nut 21 is shifted toward the post or the turn buckle rotated so as to draw the rod 22 toward the post the brace member will be carried therewith, owing to the fact that the rod 13 or 22 is connected with said brace member and moves with the tightening device and by such arrangement the post can be moved to a perpendicular position and maintained in such position unless the nut is shifted away from the post or the turn buckle rotated in an opposite direction and by such arrangement the convenient tightening of the brace member can be had.

What I claim is:—

1. A post brace comprising the combination with a post, of a V-shaped brace member 40 abutting against the post and having its lower end flattened to provide a foot, said foot being apertured, a grooved supporting plate for said foot, a coupling surrounding the post, a tightening device engaging the coupling, and a connecting rod attached at one end to said tightening device and at its other end mounted in the grooved plate, that end of the connecting rod which is mounted in the grooved plate provided with a hook 50 extending through the aperture in the foot of the brace member, said plate constituting means for maintaining the hook in engagement with the foot.

2. A post brace comprising the combination with a post, of an inclined brace member abutting thereagainst and having its lower end provided with an apertured foot, a coupling member surrounding the post, a tightening device connected with said coupling member, a grooved supporting plate for said foot, and a connecting rod having one end attached to the tightening device and its other end seated in the groove of said plate, that end of the rod mounted on said plate provided with a hooked end, extending

through the aperture in the foot, said plate constituting means for maintaining said hook in engagement with the foot.

3. A post brace comprising the combination with a post, of an inclined brace member 70 abutting thereagainst and having its lower end provided with an apertured foot, a coupling member surrounding the post, a tightening device connected with said coupling member, a flanged supporting plate, said plate adapted to receive said foot, said foot surrounded by the flange of the plate, said plate having its upper face formed with a groove, and a connecting rod having one end attached to the tightening device and its 75 other end seated in the groove of said plate, that end of the rod mounted on said plate provided with a hook adapted to extend through the aperture in said foot, said plate maintaining the hooked end of said rod in 80 engagement with said foot.

4. A post brace comprising an inclined brace member adapted to abut against the upper portion of the post and provided with a supporting foot at its opposite end, a tension rod detachably connected to the foot portion of the brace member, means for removably attaching the tension rod to the base of the post comprising complementary members detachably connected to one another and adapted to embrace the base of the post, and a device serving to support the said foot of the brace member and to retain the tension rod in engagement with said foot.

5. A post brace comprising an inclined 100 brace member adapted to abut against the upper portion of the post at one end and provided with a supporting foot at its opposite end, a tightening device removably attached at one end to the supporting foot of the 105 brace member, means for attaching the opposite end of the tightening device to the base of the post comprising a pair of segmental members provided with coöperating hooks and eyes whereby said members may 110 detachably embrace the base of the post, the tightening device being attached to one of said members, and a plate recessed to receive the foot of the brace member to support the latter and grooved to receive said 115 tension rod to retain the latter in engagement with said foot.

6. A post brace comprising an inclined brace member adapted to abut against the upper portion of a fence post and having a 120 horizontally arranged apertured foot at its lower end, a tensioning rod attached to the base of the fence post and extending beneath the foot of the brace member and having an up-turned hook which engages in the aperture thereof, and a device serving to support the said foot of the brace member and to retain the latter in coöperative relation with the hook of the tensioning rod.

7. The combination of a fence post, an in- 130

clined brace member angle shaped in cross section and having its upper end straddling said post, the flanges of the brace member co-operating with the opposite sides of the post 5 to prevent relative lateral displacement of the post and brace member, the lower end of the brace member being flattened, a flanged plate to receive the said flattened end and a tensioning device connecting the post and the

said plate which co-operates with the lower 10 end of the brace rod.

In testimony whereof I have hereunto set my hand in presence of two subscribing witnesses.

HENRY J. FRITZ.
